UNITED STATES PATENT OFFICE

159,471

SKATE CARRYING BAG

Barbara N. Chour, Milwaukee, Wis.

Application July 2, 1948, Serial No. 147,343

Term of patent 3½ years

(Cl. D58—2)

To all whom it may concern:

Be it known that I, Barbara N. Chour, a citizen of the United States, residing at Milwaukee, in the county of Milwaukee and State of Wisconsin, have invented a new, original, and ornamental Design for a Skate Carrying Bag, of which the following is a specification, reference being had to the accompanying drawing, forming a part hereof.

In the drawing:

Fig. 1 is a front elevational view of a skate carrying bag showing my new design;

Fig. 2 is a top view of the bag; and

Fig. 3 is a rear elevational view thereof.

I claim:

The ornamental design for a skate carrying bag, substantially as shown.

BARBARA N. CHOUR.
